UNITED STATES PATENT OFFICE.

CLYDE W. MUMMERY, OF RIVERTON, WASHINGTON.

OIL-BURNER.

1,160,314.

Specification of Letters Patent. Patented Nov. 16, 1915.

Application filed February 13, 1915. Serial No. 7,957.

To all whom it may concern:

Be it known that I, CLYDE W. MUMMERY, citizen of the United States, residing at Riverton, in the county of King and State 5 of Washington, have invented a certain new and useful Improvement in Oil-Burners, of which the following is a specification.

My invention relates to improvements in fluid fuel burners, and the object of my invention is to provide a burner that shall be simple in its plan of construction, reliable and efficient in its operation and that shall be adapted to burn fluid fuel, as mineral oil or gas, and which shall be further adapted 15 to generate steam and mix such steam with the vapor of the mineral oil or with the gas employed as fuel before such vapor or gas reaches the point of combustion. I accomplish this object by devices illustrated in 20 the accompanying drawings, wherein—

Figure 1 is a view in side elevation of a structure embodying my invention, showing a portion of one of its parts broken away more clearly to show other parts; Fig. 2 is 25 a plan view of a detail of the same; Fig. 3 is a view in vertical cross-section of the same on broken line *x*, *x* of Fig. 1; and Fig. 4 is a view of the same in vertical longitudinal section on broken line *y*, *y* of Fig. 3.

Referring to the drawings, throughout which like reference numerals indicate like parts, 5 is a hollow superheater, preferably of cast iron and of rectangular form, which is provided with a screw-threaded inlet passageway 6 extending through its bottom wall 8 at one of its corner portions and with an outlet passageway 7 that extends through said bottom wall 8 at the corner portion that is diagonally opposite the inlet passageway 6, and which is further provided with a plurality of air passageways 9 which extend upwardly through the bottom wall 8 and the top wall 10 and through integral annular walls 11 which are indicated by circular dotted lines in Fig. 2, which annular walls 11 serve to unite the bottom wall 8 with the top wall 10.

A steam generator 12, preferably of cast iron, is disposed beneath one edge portion of the superheater 5 to extend throughout the length thereof and is provided at one of its end portions with an outlet passageway 13 which is connected with the inlet passageway 6 of the superheater 5 by means of a screw-threaded nipple 14 while its other end portion is provided with an inlet passageway

to which is connected a water supply pipe 15, as more clearly shown in Fig. 4, whereby water may be admitted into the generator 12 for making steam which may flow therefrom into the superheater 5. The steam generator 12, preferably is formed to be oblong in cross-section in order that for a given quantity of water contained therein a greater area of its inner surface may be in contact with such water thereby more rapidly to generate steam.

Connected with the outlet passageway 7 of the superheater 5 is one end of an elbow 16 into the other end of which is screwed one end of a pipe 17 which pipe 17 extends parallel with and beneath that edge portion of the superheater 5 opposite to and parallel with the generator 12, while the other end of said pipe 17 connects with one end 75 of a U shaped pipe fitting 18 whose other end is connected with one end of a tubular burner-tip 19 whose other end is closed by a cap 20. The pipe 17 is preferably formed to be oblong in cross-section between its 80 end portions to present a greater area of its internal surface to a contact with a given volume of fluid passing therethrough than it would if it were of cylindrical form throughout its length, and for like reasons 85 the tubular burner-tip 19 is of semi-circular cross-section, as more clearly shown in Fig. 3. The tubular burner-tip 19 is provided with a plurality of holes 21 through its wall which are disposed in a row along the uppermost portion of such wall through which holes 21 fluid fuel may be emitted to produce a flame that shall be directed vertically upward against the bottom of the superheater 5, and such burner-tip 19 is provided 90 with a plurality of other holes 22 through its wall which holes 22 are disposed in a row along a line that is approximately forty five degrees from the row of the holes 21 on that side thereof that is nearer the generator 12, 100 as more clearly shown in Fig. 3, through which holes 22 may be emitted fluid fuel whose flame will be directed against the adjacent side of said generator 12.

A fluid fuel supply pipe 23 leading from 105 a source of fluid fuel supply (not shown) has its delivery end connected with the elbow 16 to adapt it to deliver fluid fuel to the interior of said elbow 16 wherefrom it may flow through the pipe 17 and through the U 110 shaped fitting 18 into the tubular burner-tip 19 to be emitted through the rows of

holes 21 and 22, respectively, and within the elbow 16 and the pipe 17 such fluid fuel may mix with the steam that flows into the elbow 16 from the interior of the superheater 5.

The structure thus described is disposed to be supported on brackets 24 and 25, the end portions of the pipe 17 resting each on one of the brackets 24 while the end portions of the generator 12 rest each on one of the brackets 25, as more clearly shown in Figs. 1 and 4. The brackets 24 and 25 are secured to the inner surface of the bottom of a pan 26 whose top edges are provided with integral flanges 27 which project outwardly therefrom in a horizontal plane, such flanges 27 being adapted to support the pan 26 and its contents when disposed within the firebox of a stove, not shown.

Within the bottom portion of the pan 26 I have provided fibrous absorptive material 33, preferably mineral wool or asbestos fiber, which when saturated with oil may serve in a wick-like manner to promote combustion in the process of putting the burner into operation.

To supply water to the steam generator 12 I have provided a water tank 28 having a removable airtight stopper 29 that is adapted to screw into a screw-threaded opening in its top wall, as more clearly shown in Fig. 4 and through the bottom wall of said water tank 28 extends one of the screw-threaded ends of a cock 30 whose lower screw-threaded end is disposed to extend through the top wall of an inclosure 31, from the lower portion of one side of which extends the supply pipe 15 whereby water may flow from the inclosure 31 into the generator 12. The lower end of an air pipe 32 is screwed into and through the top wall of the inclosure 31 to extend upwardly adjacent to the vertical wall of the tank 28 to a point as high as the top of such tank 28, through which air pipe 32 air may always find access to the interior of the inclosure 31.

The operation of a burner embodying my invention, as thus shown and described, is as follows: The cock 30 is turned to a closed position and the stopper 29 is removed from the opening in the top of the tank 28 whereupon such tank 28 is filled with water and then the stopper 29 is replaced and screwed tightly to make such tank 28 airtight, thereupon the cock 30 is opened to permit water to flow into the inclosure 31 wherefrom such water will then find its way through the water supply pipe 15 into the generator 12 and such flow of water through the cock 30 will continue to flow until the surface of the water in the generator 12 rises to a plane level with the lower end of the cock 30 within the inclosure 31 whereupon the surface of the water within the inclosure 31 will act to seal the passageway through the cock 30

to prevent air from the pipe 32 finding its way upwardly through such cock 30 into the tank 28 to replace the water as such water percolates downwardly through the small passageway of the cock 30 into the 70 inclosure 31 and since no air can get into the tank 28, so long as the water level covers the lower end of said cock 30, no water will flow downwardly from the tank 28 through the cock 30 because such lessening of the 75 amount of water in the tank 28 would tend to form a vacuum therein. Thus, by such arrangement of the tank 28, the cock 30, the inclosure 31, the pipe 15 and the generator 12, it is obvious that as the water in the 80 generator 12 is converted into steam thus to lower its level sufficiently to cause the level of the water in the inclosure 31 to fall sufficiently to unseal the mouth of the lower end of the cock 30, then water will immediately commence again to flow from the tank 28 to replace the water in the generator 12 as such water is converted into steam, whereby the level of the water in the generator 12 is constantly maintained at a constant height irrespective of the rate at which such water is converted into steam. After the tank 28 has been filled with water and the stopper 29 is screwed into its position to close tightly the opening in the top 95 of the tank 28, then fluid fuel, as mineral oil, is admitted into the elbow 16 wherefrom such oil flows through the pipe 17 and through the U shaped fitting 18 into the burner-tip 19 to flow out of the holes 21 and 22 to drop into the bottom of the pan 26 to saturate the fibrous absorptive material 33 and when enough oil has dripped into the pan 26 thoroughly to soak the absorptive material 33 then such oil is ignited and the 100 flame of such burning oil will heat the generator 12 to generate steam therein and will heat the superheater 5 to superheat the steam flowing therethrough from the generator 12 and will heat the pipe 17 to vaporize the fuel oil flowing therethrough whereby such fuel oil will be converted into vapor or gas which will be mixed with superheated steam before reaching the burner-tip 19, thus to be emitted from the holes 21 and 22 in the form of 105 a highly combustible mixture which will produce a blue flame that will deposit no carbon and which will be so directed that the superheater 5 will be substantially at the same temperature throughout all its portions.

In some cases it may be found desirable to dispose the pipe 17 so that its end adjacent to the elbow 16 may be higher than its end adjacent to the U shaped fitting 18 thus to cause 115 mineral oil more readily to flow toward the burner-tip 19 in the initial operation of lighting the burner.

While I have shown my preferred form of cross-section of the pipe 17, the burner-tip 130

19 and the generator 12 it is manifest that such form of cross-section may be widely modified, and all parts of the structure may be changed with respect to their forms, dimensions and arrangement without departing from the spirit of my invention.

What I claim is:

An oil burner of the class described, comprising a supporting tray, a hollow rectangular superheater having inlet and outlet passages disposed at opposite corners thereof and located above said tray, a steam generator mounted within the tray and extending beneath one side of the superheater and having communication with the inlet passage thereof, a supply pipe extending through a wall of the tray and communicating with the generator, a burner pipe extending longitudinally of the center of the

tray and provided with a series of burner orifices arranged vertically above the center of the pipe to project flames against the superheater, said burner pipe being further provided with a second series of orifices discharging laterally against the steam generator, a pipe connecting said burner pipe and the outlet of the superheater and underlying the side of the superheater opposite the steam generator, and a fluid fuel supply pipe leading into the last-mentioned pipe adjacent its connection to the superheater.

In witness whereof, I, hereunto subscribe my name this twenty fifth day of January, A. D., 1915.

CLYDE W. MUMMERY.
